ABSTRACT

A weaving machine of the type having at least at one side a weft inserting device and at the other side, carried by the reed, a catching means and a clamping means cooperating therewith, for receiving, catching and tensioning the weft threads launched through the weaving shed, has a guiding piece mounted on the reed which is adjustable in the weft direction and is provided with a receiving channel situated in the insertion path of the weft yarn, which channel deviates at its end remote from the weft inserting device into the beating up direction of the reed and is open towards the beating up side along its complete length, the catching means being positioned in front of the deviated receiving channel end and being movable from a receiving position, corresponding with the retracted reed position, in the weft direction relative to the clamping means which is also carried by the reed towards a clamping position corresponding with the beating up position of the reed.

WEAVING MACHINE

CROSS-REFERENCE TO RELATED APPLICATION

This is a continuation-in-part of abandoned application Ser. No. 264,645, filed June 20, 1972.

BACKGROUND OF THE INVENTION

The invention relates to a weaving machine of the type in which at least at one side a weft inserting device is provided and at the other side a device is provided, carried by the reed and having a catching means and a clamping means cooperating therewith, for receiving, catching and tensioning the weft threads launched through the weaving shed.

Such a weaving machine is described in Dutch pat. application no. 7016178. In that machine the catching means which, in combination with the clamping means, serves to tension a weft length inserted into the weaving shed by the weft inserting device at the moment of the beating up by the reed, has a fixed position on the reed beam, viz. at the end of the tunnel delimited by the plurality of substantially U-shaped reed blades. As a consequence thereof, when weaving smaller cloth widths than the maximum cloth width for which the machine has been designed, it has to be operated with weft lengths corresponding with the maximum cloth width in order to have the weft ends, projecting beyond the cloth, caught by the catching means and have them clamped in cooperation with the clamping means.

SUMMARY OF THE INVENTION

The invention aims at improving said machine so that smaller cloth widths may be woven on a machine adapted for a predetermined maximum cloth width, while retaining the tensioning function during the beating up by the reed with correspondingly shorter weft lengths.

Therefore according to the invention a guiding piece mounted on the reed is adjustable in the weft direction and is provided with a receiving channel situated in the insertion path of the weft yarn, which channel deviates at its end remote from the weft inserting device into the beating up direction of the reed and is open towards the beating up side along its complete length, the catching means being positioned in front of the deviated receiving channel end and being movable from a receiving position, corresponding with the retracted reed position, in the weft direction relative to the clamping means which is also carried by the reed towards a damping position corresponding with the beating up position of the reed.

As a result of this, when it is desired to weave smaller cloth widths, the device comprising the catching means and the clamping means may be shifted relative to the reed, such that said device is located at a shorter distance from the weft inserting device, and shorter weft lengths may be used.

In the machine according to the above mentioned patent application a sucking nozzle is positioned at the side remote from the weft inserting device, said nozzle serving to suck the leading end of an inserted weft thread, and, after the inserted weft thread has been beaten up by the reed into the cloth and subsequently the weft end projecting beyond the edge of the cloth has been cut off, to suck off said end.

Further according to the present invention a sucking nozzle is positioned with its sucking aperture in the de-

viated portion of the path of the weft yarn, between the catching means and the beating up line and is mounted together with the guiding piece, the catching means and the clamping means for adjustment in the transverse direction on the machine.

From U.S. pat. application Ser. No. 83,176 a weaving machine is known in which for inspecting purposes at the side remote from the weft inserting device a weft detection device is provided which mainly comprises a light source and a light sensitive resistance cooperating therewith, the light source being provided in a channel opening into the guiding channel for the weft thread, and the light sensitive resistance communicating through a second channel with the thread guiding channel opposite to the opening of the light source channel, in order to receive a quantity of light which changes when a weft thread passes.

Now in accordance with the present invention a thread detection device has been provided such that the channels containing the light source and the light sensitive resistance open into the receiving channel in the guiding piece.

BRIEF DESCRIPTION OF THE DRAWINGS

FIG. 1 is a diagrammatic perspective view of part of a weaving machine according to the invention;

FIG. 2 is a vertical section of a slightly modified form of reed, taken just outside the edge of the warp sheets, looking in the direction of weft insertion, showing the reed in its retracted position, the catching means and the clamping means being shown in elevation;

FIG. 3 is an elevation of the catching means and the clamping means as seen in the warp direction, looking from the left in FIG. 2;

FIG. 3a is a fragmentary plan view of the catching means and the clamping means of FIG. 3;

FIG. 4 is an elevation of a portion of the reed and the guiding piece, slidably mounted thereon and accommodating the thread detection means;

FIG. 5 is a wiring diagram of the thread detection means and

FIGS. 6-8 are schematical plan views showing three consecutive stages in the cooperation between the catching means and the clamping means.

DESCRIPTION OF THE PREFERRED EMBODIMENTS

In FIG. 1 the reference numbers 1 and 2 each indicate a side portion of the frame of the weaving machine. The reed, indicated at 3 is swingable in the direction of the arrow I around a pivot shaft (not shown) between a retracted position (as shown in the drawing) and a beating up position.

The reed proper is formed in a known manner by a series of reed blades 4 positioned closely adjacent each other in the transverse direction of the machine, said reed blades being at their lower ends received in the reed beam 5 or 5a and at their upper ends projecting into a rail 6.

The weaving shed has been indicated at 7 and is delimited by the upper warp 8, the lower warp 9 and the reed blades 4. The cloth that has already been woven is indicated at 10 and extends above the temple 12. The beating up line is indicated at 13, e.g. the line along which a weft inserted through the weaving shed is beaten up into the cloth by the reed in its operative beating up position.

The weft insertion may be effected by means of a flowing fluid, such as pressurized air. Accordingly a blowing nozzle 14 is applied at one side of the weaving machine.

The transport of a weft launched by the blowing nozzle 14 in fact takes place through the tunnel 15 which is delimited by U-shaped notches in the reed blades 4 which notches are open in the direction of the beating up line 13. The transport of the weft through the weaving shed and through the reed tunnel 15 respectively may, particularly with the larger weaving widths, be assisted by means of intermediate blowing nozzles carried by the reed. For the sake of clarity such auxiliary blowing nozzles are not shown.

At the end of the reed remote from the blowing nozzle 14 a guiding piece 16 or 16a is mounted. Said guiding piece has a projecting foot 17 or 17a engaging in a corresponding longitudinal groove of the reed beam 5 or 5a and is fixed by means of a clamp 18 slidably engaging the rail 6. A projecting portion 19 of the guiding piece fits in the reed tunnel 15.

FIG. 2 is a vertical section which shows the side of the guiding piece 16a that faces toward the blowing nozzle 14.

FIG. 1 shows the side facing away from the blowing nozzle 14 of a slightly modified form of guiding piece 16. In the form shown in FIG. 1, the guiding piece 16 has a rectangular projecting foot 17 that fits under a rectangular shoulder of the reed beam 5, whereas in FIG. 2 the guiding piece 16a has a rounded foot 17a fitting in a rounded groove formed in the reed beam 5a.

Both in FIG. 1 and in FIG. 2, the position of the guiding piece along the reed beam can be adjusted to fit a different width of cloth by first loosening the clamp 18, then sliding the guiding piece to a new position along the reed beam, and then retightening the clamp 18 on the rail 6.

The guiding piece portion 19 is provided with a catching channel 20, of which the end (FIG. 2) facing the blowing nozzle 14 opens into the reed tunnel 15 and of which the other end is deviated into the beating up direction of the reed and ends in an opening 20a (FIG. 1). Further the catching channel 20 is open along its full length towards the beating up line 13 because of the presence of a slot 20b.

Dependent on the desired cloth width the guiding piece 16 may be fixed on the reed at a greater or smaller distance from the blowing nozzle 14.

A block 21 is slidably mounted along the lower side of the reed beam 5 or 5a (see also FIGS. 2 and 3) and can be secured in place in any desired position along the reed beam by means of a set screw 21a mounted in an upstanding bracket 21b of the block 21. The block 21 carries the catching means 22 and the clamping means 23 cooperating therewith. The catching means 22 and the clamping means 23 are pivotally mounted around a common shaft 24 mounted in the bracket 21b on the block 21 and are mutually coupled by a spring 25 tending to pivot the two means toward one another into the clamping position. The clamping means 23 normally engages an abutment screw 26 carried by the block 21, whereas the catching means 22 at a boss 27 thereon, is pivotally connected to an actuating rod 28 which extends obliquely below the temple 12 to a pivot point 29.

FIG. 3 shows the catching means 22 in the weft end receiving position. In this position, which corresponds with the retracted reed position, e.g. the position in which a weft may be inserted through the reed tunnel 15, the receiving eyelet 30 of the the catching means 22 is direction opposite the opening 20a of the catching channel 20 in the guiding piece 16, and lies in a plane which is slightly spaced in the beating up direction from the opening 20a. Therefore the leading end of a weft inserted by the blowing nozzle 14 into the weaving shed will be deviated by the guiding piece 16 into the beating up direction of the reed or the warp direction and will thereby extend through the receiving eyelet 30 (see the stage according to FIG. 6). This extension of the leading end of the weft through the eyelet 30 is promoted in that at the side of the eyelet 30 remote from the channel opening 20a the receiving end of a suction nozzle is positioned. This suction nozzle, which may be constituted by a simple tubular nozzle 31, is carried on the slidable block 21 by means of clamps 32 and 33 secured to the bracket 21b, and therefore moves together with the reed.

The suction nozzle 31 is shown in side elevation in FIG. 2. FIG. 3 is a detail in that it is an elevation showing only the catching means and the clamping means, looking from the left in FIG. 2. Thus the suction nozzle 31 is not present in FIG. 3, but the location of the suction nozzle 31 is indicated by shadow lines in FIG. 3.

As shown in FIG. 3a, the clamping means 22 is provided with a thickened clamping head 34. When the reed is in its retracted position, the rod 28 is under tension, and the catching means 22 is thereby pulled toward the right in FIG. 3, away from the clamping means 23. The abutment screw 26 prevents the clamping means 23 from following the catching means 22 as the catching means 22 is pulled to the right in FIG. 3 by the rod 28.

When the reed 3 moves in the beating up direction e.g. to the left as seen in FIG. 2, the rod 28 is pivoting around its pivot point 29, as a result of which the thrust of the rod 28, combined with the action of the spring 25 rotates the catching means 22 about the shaft 24 to the left (as seen in FIG. 3). The catching means 22 with its clamping head 34 (FIG. 6) is thus moved towards the clamping means 23 which is still held against the abutment screw 26 by the action of the spring 25. Thus before the reed has arrived in the beatup position, the weft end w, extending through the eyelet 30, becomes clamped as shown in FIG. 7 when the clamping head 34 of the catching means 22 engages the upper end of the clamping means 23. Thereafter the catching means 22 now carrying with it the clamping means 23 continues to be turned by the thrust of the rod 28 through a certain distance to the left (as seen in FIG. 3), away from the abutment 26, whereby the weft is drawn taut (see FIG. 7).

An ejector blade 35, shown in FIG. 3 3a but omitted from FIG. 2, extends through and is movable in a vertical slot 35a which is formed in the thickened clamping head 34 of the catching means 22. The ejector blade 35 is pivotally mounted on a projecting arm 23a of the clamping means 23. Fixed in the end of the blade 35 is a laterally projecting pin 36 which is guided in a vertical groove 37 cut in one side of the slot 35a which is formed in the clamping head 34. When the catching means 22 first moves toward the left from the catching position according to FIG. 3, before the clamping head

of the catching means strikes the clamping means 23, the action of the groove 37 on the pin 36 pulls the ejector blade 35 downward until the rounded under side of the blade 35 cams the weft thread end w aside, whereby the upper end of the blade 35 slides downward past the weft end so that the upper end of the blade 35 arrives below the weft thread end before the thread end is clamped between the clamping means 23 and the clamping head 34.

When the reed is again retracted from the beating up position, the means 22 and 23 first move together to the right (as seen in FIG. 3) until the clamping means 23 again abuts the abutment screw 26, whereafter the catching means 22 alone is pulled further to the right by the rod 28. Thereby the action of the groove 37 on the pin 36 causes the ejector blade 35 to move upwardly. The concave upper side of the blade 35 thus engages the weft thread end, and causes said end to slide away over the upper side of the clamping portion 34 and to be completely sucked into the sucking nozzle 31 as shown in FIG. 8. Said weft thread end then does not form an obstruction for the next weft and may be cut off at this moment by energization of the electrically operated cutting device 38, which is similar to the conventional cutting device 38a used for cutting the weft thread from the thread supply, whereafter the weft thread end is discharged by the sucking nozzle 31.

Finally with reference to the diagram of FIG. 5 the thread detection device cooperating with the guiding piece 16 is described. Said thread detection device is mainly constituted by the light source indicated at 40 in the diagram of FIG. 5 and by the light sensitive resistance indicated at 41. In reality the light source 40 supplied by the voltage source 42 is provided in a bore 43 (FIG. 4) provided in the guiding piece 16, said bore opening into the catching channel 20. For that purpose the light source 40 is executed as a miniature incandescent lamp, a GaAs diode or similar small light source. The second bore in the guiding piece 16 has been indicated at 44 and opens from the opposite side into the catching channel 20 and contains the light sensitive resistance 41 which may be formed by a CdS resistance or photodiode.

Each time when a weft inserted from the other side into the weaving shed arrives with its leading end in the guiding piece and is caught by the catching means, this means a change in the quantity of light received by the resistance 41 from the light source 40.

The light signal obtained in this way forms an indication that a weft has actually been inserted from the other side of the weaving machine. Said light signal may be transformed, as indicated in the diagram of FIG. 5, by an amplifier 27 into an electric signal which is required to keep energized the drive of the weaving machine.

I claim:

1. A weaving machine of the type having at least at one side a weft inserting device and at the other side, carried by the reed, a catching means and a clamping means cooperating therewith, for receiving, catching and tensioning weft threads launched through a weaving shed, characterized by a guiding piece mounted to the reed adjustable in the weft direction and provided with a receiving channel situated in the insertion path of the weft thread, which channel deviates at its end remote from the weft inserting device into the beating up

direction of the reed and has an opening on its beating up side extending along its complete length, the catching means being spaced in the beating up direction from the deviated end of the receiving channel, and being movably mounted on the reed for movement, generally parallel to the shed, from a weft thread-receiving position to a clamping position in which the weft thread is clamped between the catching means and the clamping means, and mechanism actuated by movement of the reed toward its beating up position for moving the catching means toward its clamping position.

2. A weaving machine according to claim 1, in which the weft inserting path is determined by a tunnel which is longitudinally open towards the beating up line and delimited by a plurality of substantially U-shaped reed blades, and wherein the guiding piece comprises a filling piece which is adjustably mounted in said tunnel.

3. A weaving machine according to claim 1 wherein said catching means comprises a catching eyelet having an escape aperture for the weft thread and a clamping surface cooperating with the clamping means, an ejection means being provided which is movable between a lower and an upper position, and having mechanism for moving the ejection means from its lower position to its upper position during movement of the catching means from its clamping position back to its receiving position, thereby ejecting the weft thread through the escape aperture of the eyelet.

4. A weaving machine according to claim 3, characterized in that the receiving eyelet is formed at the end of a lever which is pivotable around a shaft substantially extending in the warp direction, around which shaft also the clamping means constituted by a lever is pivotable from an abutting position into the weft direction together with the catching means brought into the clamping position.

5. A weaving machine according to claim 1 in which a cutting device for cutting the weft thread ends projecting beyond the relative cloth edge is provided at the side remote from the weft inserting device and wherein further a sucking nozzle is provided for sucking in the head ends of the inserted weft threads and subsequently sucking off the cut thread ends, characterized in that the sucking nozzle is provided with its sucking opening in the deviated portion of the path of the weft yarn, adjacent to the catching means and is adjustable in the transverse direction of the machine together with the guiding piece, the catching means and the clamping means.

6. A weaving machine according to claim 1 in which for inspecting the weft at the side remote from the weft inserting device a thread detection device is provided, said device substantially comprising a light source and a light sensitive resistance cooperating therewith; the light source being provided in a channel opening into a guiding channel for the weft thread, the light sensitive resistance communicating by a second channel with the thread guiding channel opposite to the opening of the light source channel, for receiving a quantity of light changing when a weft thread passes, characterized in that the thread detection device is provided such that the channels containing the light source and the light sensitive resistance open into the receiving channel in the guiding piece.
